HUBERT A. MYERS, OF TOLEDO, OHIO.

WINDOW REGULATOR.

Application filed December 13, 1926. Serial No. 154,326.

This invention relates to window regulators for controlling the position of windows in vehicles such as automobiles, motor boats and the like, and more particularly to the connector arranged between the window and the regulating mechanism proper.

It has long been a desideratum among automobile manufacturers and engineers to provide means for efficiently raising and lowering the windows of vehicles and at the same time overcome the objectionable noise heretofore attendant upon use of such mechanisms. A large part of the noise thus engendered is due to rattle between the window and adjacent parts of the vehicle including the regulator mechanism. Such rattle is caused either by vertical movements of the window as the car body bounces during travel or by lateral vibratory movements of the window resulting in a series of spaced contacts of the window with the adjacent frame or portions of the regulator mechanism. Spring clamps or bumpers tending to press the window against the frame to prevent chatter cannot be employed without so increasing the friction during the raising and lowering movements as to render the working of the regulator mechanism too difficult for ladies and children, and when the window is left free to easily slide under the impulses given by the regulator mechanism it is also free to vibrate with the car body. The principal object of the present invention is the arrangement of a resilient connector between the window and its regulator mechanism that will prevent this objectionable rattle of the window against its side frames as well as against the adjacent portions of the regulator mechanism, and which will transmit the required impulses from the regulator mechanism to the window.

A further object of my invention is the arrangement of a resilient connector upon the operating arm of the regulator mechanism and engaging the window whereby the window will be held against undue vibratory movements and which will aid in preventing the transmission of shocks from the regulator mechanism to the window.

Other objects and advantages will be apparent from the following description, where reference is made to the accompanying drawings illustrating preferred embodiments of my invention and wherein similar refer-

ence numerals designate similar parts throughout the several views.

55

In the drawings:

Fig. 1 is a side elevation of the operating lever arm of a window regulator and associated mechanism, parts being broken away.

Fig. 2 is an enlarged detail sectional view 60 taken substantially on the line 2-2 of Fig. 1.

Fig. 3 is a detail vertical section taken substantially on the line 3-3 of Fig. 2, and

Fig. 4 is a vertical sectional view showing a slightly modified embodiment of my invention, and

Fig. 5 is a vertical sectional view showing another modification of my invention.

Referring now to the drawings, the numeral 5 designates a fulcrum plate or frame member adapted to be secured in the usual or any desired manner upon the body of a vehicle adjacent a window frame and arranged to support a shaft 6 adapted to be clutch-connected with an operating handle 7 (not shown) and carrying a pinion 7 normally meshing with an arcuate rack 8 fixed upon the operating lever arm 9. It is to be understood that the above described regulator mechanism is intended to be typical of regulator mechanism now used to a considerable extent upon automobiles, and that the claimed disclosure herein is adapted for use with any desired form of regulator mechanism. In the illustrated embodiment the operating lever arm 9 is a lever of the third order, the weight being supported upon the free end of the lever, its fulcrum being at the opposite end of the lever upon the fulcrum pin 10 while the power is applied intermediate 90 the ends of the lever through the rack 8. The weight of the window 11 and lever arm 9 is adapted to be counterbalanced wholly or in part by means of a counterbalancing spring 12 attached at one end of the fulcrum pin 10 and secured to a bracket 13 extending from the lower portion of the fulcrum plate 5 (note Fig. 1).

The lower portion of the window 11 is ordinarily fitted into a substantially U-shaped strip 14 against which bears the connector whereby movement is imparted to the window from the regulator mechanism. I have provided an improved form of connector adapted to accomplish all that has 105 been done by the connectors heretofore used

and in addition aid in absorbing shocks that might be transmitted from the regulator mechanism to the window as well as tend to hold the window against vibration in either 5 vertical or lateral directions. Toward this end I have illustrated in Figs. 1-3 a connector 15 formed as a resilient roller having a concave periphery of slightly lesser curvature than the curvature of the bight portion of the strip 14 carried by the lower edge 10 of the window 11. As best illustrated in Fig. 2 the roller 15 is formed as a coiled wire spring with its convolutions of progressively varying diameters and with its extremities 15^a (note Fig. 3) closely encircling a journal bolt 16 so as to enable the ready rotation of the connector 15 upon the bolt 16. The end convolutions of the connector 15 are initially spaced from each other by a distance slightly 20 less than the distance shown in Fig. 2, whereby the end convolutions will be forced apart by the strip 14 of the window 11 when the connector is mounted upon the window. This arrangement causes a lateral distortion of 25 the connector 15 to provide oppositely directed tensions tending to maintain the window centrally of the connector 15 and holding it against lateral vibration during the travel of the vehicle. The bolt 16 is preferably 30 secured in the free extremity of the lever arm 9, substantially as shown in Fig. 1. This pinching grip of the convolutions of the connector 15 aids in maintaining lateral stability of the window 11, but has but little 35 effect in controlling vertical vibrations of the window, as during travel of the vehicle over rough streets. To maintain vertical stability of the window 11 I preferably mount the anchor strip 17 so that its lower flange 17^a 40 is spaced from the lowermost portion of the strip 14 of the window by a distance less than the diameters of the end coils of the connector 15. The vertical portion of the anchor strip 17 may be spot welded or otherwise 45 suitably secured to the strip 14, enabling maintenance of the desired positioning of the strips 14 and 17 during the raising and lowering movements of the window. The sides 50 of the strip 17 may be left open to enable the insertion of the connector 15 into the space between the strips 14 and 17 from either side of the strip 17. Or the connector may be inserted from the front by tilting the connector 15 sufficiently to permit the insertion 55 of the top portion of its outermost coil into the space beyond the lowermost portion of the strip 14, whereupon the lever arm 9 and connector is swung to substantially the position shown in Fig. 2, the several convolutions 60 of the connector being distorted during such swinging movement to permit the ingress of the connector into the space between the strip 14 and the flange 17^a. When the connector is properly positioned it will resist 65 up and down movements of the window rel-

atively to the lever arm 9. Vertical movement of the window in either direction will tend to compress the convolutions of the connector 15, and the connector will absorb the shocks tending to produce the vertical movements of the window. 70

When it is desired to raise or lower the window 11 from its then position, it is only necessary to turn the pinion 7 in the proper direction to swing the operating lever arm 9. 75 The movement of the free extremity of the lever arm 9 will be transmitted to the window 11 through my improved connector 15, which may roll or slide along the strips 14 and 17 to permit the ready swinging movement of the lever arm 9. Sudden shocks that may be imparted to the lever arm through 80 jerky turning of the pinion 7, etc., may be absorbed by the connector 15 and prevent it from reaching the window itself. 85

In Fig. 4 I have shown a slightly modified embodiment wherein my improved connector 85 may be directly secured upon the lever arm 9 without the interposition of the journal bolt 16. The connector 18 therein shown is 90 formed as a coiled wire spring with convolutions of progressively varying diameters and with the endmost convolutions initially spaced substantially as are those in the above described embodiment of my improved connector 15, but the ends 18^a are bent into substantially parallel positions extending laterally beyond one of the end convolutions to enable their being readily passed through spaced apertures 19 in the lever arm 9. With this 95 construction the ends 18^a of the connector 18 are thrust through the apertures 19 and then clinched, substantially as shown in Fig. 4, to enable the permanent mounting of the connector upon the lever arm. With this construction the connector 18 is not free to rotate, but may slide upon the bight portion of the strip 14 and flange 17^a during the swinging 100 movements of the lever arm 9. 105

In Fig. 5 I have shown a further modification of my invention wherein my improved connector may be directly connected upon the lever arm 9 in the same manner as in the embodiment shown in Fig. 4, but the contour of the spring connector is shaped to co-operate 110 with a concave strip 14^a upon the bottom of the window. The periphery of the coiled spring connector 20 is made convex substantially as shown with the coils so spaced as to enable contact between the connector and 115 strip 14^a at a plurality of points. The positioning of the coils of largest diameter within the concavity in the strip 14 serves to hold the strip and attached window against lateral vibration, while the resiliency of the spring 120 connector serves to absorb vertical vibrations of the window. 125

While it will be apparent that the illustrated embodiments of my invention herein disclosed are well calculated to adequately 130

fulfill the objects and advantages primarily stated, it is to be understood that the invention is susceptible to variation, modification and change within the spirit and scope of the 5 subjoined claims.

Having described my invention, I claim—

1. The combination with a window carrying a strip upon its lower extremity and a window regulator mechanism having an operating arm, of a resilient connector comprising a coiled wire spring mounted upon said arm and having its periphery shaped to substantially conform with the shape of the lower portion of said strip.
- 15 2. The combination with a window carrying a strip upon its lower extremity and a window regulator mechanism having an operating arm, of a resilient connector comprising a coiled wire spring having its end convolutions of greater diameter than its central convolutions and initially spaced from each other by a distance less than the thickness of the lower portion of said strip, the periphery of the connector being normally in contact with the lower portion of said strip.
- 20 3. The combination with a window carrying a substantially U-shaped strip on its lower portion and an anchor strip having a flange in spaced alignment with the bight portion of the U-shaped strip, of a window regulator mechanism having an operating arm carrying a resilient connector comprising a coil spring having a concave periphery adapted to receive the bight portion of said U-shaped strip, the end convolutions of said connector being initially spaced from each other by a distance less than the thickness of the bight portion of said U-shaped strip.
- 25 4. The combination with a window carrying a substantially U-shaped strip on its lower portion and an anchor strip having a flange in spaced alignment with the bight portion of the U-shaped strip, of a window regulator mechanism having an operating arm carrying a resilient connector comprising a coil spring having a concave periphery adapted to receive the bight portion of said U-shaped strip, the end convolutions of said connector being initially spaced from each other by a distance less than the thickness of the bight portion of said U-shaped strip.
- 30 5. The combination with a window carrying a substantially U-shaped strip on its lower portion and an anchor strip having a flange in spaced alignment with the bight portion of the U-shaped strip, of a window regulator mechanism having an operating arm carrying a resilient connector comprising a coil spring having a concave periphery adapted to receive the bight portion of said U-shaped strip, the convolutions of said connector being greater than the distance between the lowermost portion of the U-shaped strip and the upper surface of the flange of the anchor strip.

spring having a concave periphery adapted to receive the bight portion of said U-shaped strip.

35

4. The combination with a window carrying a substantially U-shaped strip on its lower portion and an anchor strip having a flange in spaced alignment with the bight portion of the U-shaped strip, of a window regulator mechanism having an operating arm carrying a resilient connector comprising a coil spring having a concave periphery adapted to receive the bight portion of said U-shaped strip, the end convolutions of said connector being initially spaced from each other by a distance less than the thickness of the bight portion of said U-shaped strip.

40

5. The combination with a window carrying a substantially U-shaped strip on its lower portion and an anchor strip having a flange in spaced alignment with the bight portion of the U-shaped strip, of a window regulator mechanism having an operating arm carrying a resilient connector comprising a coil spring having a concave periphery adapted to receive the bight portion of said U-shaped strip, the convolutions of said connector being greater than the distance between the lowermost portion of the U-shaped strip and the upper surface of the flange of the anchor strip.
